Term of patent 14 years

Int. Cl. D24—04, 99

U.S. Cl. D16—1 R

FIG. 1 is a perspective view of the intravenous clamp taken from the front and to one side of the clamp, and from above the clamp;

FIG. 2 is a perspective view of the clamp taken from the front and from the other side of the clamp, and from above the clamp;

FIG. 3 is an elevation of one side of the clamp;

FIG. 4 is an elevation of the other side of the clamp;

FIG. 5 is an end elevation of the clamp;

FIG. 6 is a top plan view of the clamp; and

FIG. 7 is a bottom view of the clamp.

The clamp shown in the drawing is intended to hold a pole to a wheelchair, for example, which, in turn, supports a bottle of medication for intravenous feeding.

I claim:

The ornamental design for an intravenous clamp, substantially as shown and described.
